UNITED STATES PATENT OFFICE

1,936,961

KITCHEN UTENSIL

Clara A. Burge, Castlewood, S. Dak.

Application October 25, 1932. Serial No. 639,511

1 Claim. (Cl. 65—12)

My invention relates generally to kitchen utensils, and particularly to an instrument which is primarily adapted to taking up, lifting, and carrying doughnuts, and which is useful also for kindred purposes.

It is an important object of my invention to provide an instrument of this type which, when employed as a doughnut lifter, will efficiently perform the functions of lifting and carrying a plurality of doughnuts, without endangering the coating of the doughnut by piercing or otherwise fracturing the same.

It is also an important object of my invention to provide a device of the character described which will positively prevent doughnuts and the like on the same from slipping and getting into an inconvenient position thereon.

It is also an important object to my invention to provide in an instrument of the type described above a special formation which shall facilitate the picking up and lifting and carrying of the doughnuts and the like and act to prevent the doughnuts or the like from falling from or shifting relative thereto.

Other objects and advantages of my invention will be apparent from a reading of the following description in connection with the drawing, wherein for purposes of illustration I have shown a preferred embodiment of the invention.

In the drawing:—

The figure is a general perspective view of an embodiment of the invention, showing in dotted lines how doughnuts may be lifted and carried thereby.

Referring in detail to the drawing, wherein like numerals refer to like parts throughout the same, the numeral 5 generally designates the embodiment which comprises a suitable handle 6 in which is fastened in any well known manner a straight rectangular shank 7 which begins to curve out of the longitudinal axis approximately at the point 8. The curvature beginning at this point off-sets the remainder of the device from the longitudinal axis of the shank 7. The half elliptical or bowed portion 9 results, and terminates in a rounded point 10.

About two-thirds of the way of the handle 6 toward the outer end of the device, it is provided with lateral projections 11 and 12 oppositely disposed and constituting guards for engaging the sides of doughnuts 13 which may be placed on the portion of the device which extends beyond the location of the guards 11, 12. The device being continuously curved from approxi-

mately the point 8, there is provided a suitable formation for facilitating entering the point 10 and subsequently the curved portion 9 under the doughnuts on the tray or other surface on which they are located, so as to facilitate lifting them. It will be obvious that when the point 10 has been entered to a sufficient distance under the doughnut that a slight downward movement of the handle 6 will result in placing the point 10 up into the opening of the doughnut, when the doughnut may be lifted simply by lifting the entire instrument, then tilting the same upwardly so that the doughnut will rest on the guards 11, 12. It will be obvious that more than one doughnut may be lifted and carried in this manner and that such a plurality of doughnuts is positively prevented from moving objectionably toward the handle 6 by the guards. Since no sharp points are presented which would be apt to be inadvertently engaged with the doughnuts so as to fracture the coating thereof, it will be obvious that the device of the invention is operable in an efficient and desirable manner.

Though I have shown and described herein a preferred embodiment of the invention, it is to be definitely understood that I do not desire to limit the application of the invention thereto, and any change or changes may be made in material and structure and arrangement of parts, within the spirit of the invention and the scope of the subjoined claim.

What is claimed is:—

A doughnut lifter comprising a handle, a shank extending axially from one end of the handle, a bowed portion on the outer end of the shank, a pair of straight short arms projecting from opposite sides of the shank where it meets the bowed portion for holding articles on the bowed portion from moving on the shank toward the handle, said pair of arms being arranged on the shank in a plane at right angles to that in which the bowed portion curves, said bowed portion and arms being of substantially uniform rectangular cross section.
